PAUL A. PITMAN, OF QUINCY, MASSACHUSETTS.

APPARATUS FOR MAKING SMALL CASTINGS.

Application filed August 6, 1926. Serial No. 127,592.

This invention relates to apparatus for making castings by the use of fluid pressure to force the molten metal from the crucible into the mold.

5 In the casting of objects by this method, particularly objects made of gold, silver and platinum, a vital factor is the time interval between the heating period and the application of fluid at a working pressure sufficient to force the metal into the mold. For example, in making small dental castings an interval of one half second in applying the working pressure to the molten metal may defeat the casting, whereas, if the interval 10 were reduced to one fifth of a second the result would be satisfactory.

Dental and other small castings have been made by the use of apparatus comprising a stationary tank or reservoir containing air or 20 nitrous oxide gas under pressure, a flexible pipe from one to two feet long for connecting the tank and the flask of the mold, and a valve operated by movement of the flask or the pipe-coupling to release the fluid 25 stored in the tank so that it may flow through the flexible pipe to the flask. The area of the connecting passageway formed by the flexible pipe, the elasticity of the rubber or other material of which the flexible pipe is made, 30 and the distance to be traveled by the fluid from the tank to the crucible retard the development of pressure in the latter so long that very small bodies of molten metal lose their fluidity during the interval above mentioned.

In view of these conditions an object of the present invention is to provide improvements in casting apparatus by which the aforesaid interval may be substantially shortened, to the end that even the smallest practicable castings, for example, dental inlays, 40 may be made.

To accomplish this result my invention provides the novel combination comprising a 45 tank or reservoir for the operating fluid, a releasing valve in the discharge port of the reservoir, a coupling device attached directly to the reservoir and movable relatively thereto, and means operable by relative movement 50 of the coupling device and the reservoir to open the valve. This combination eliminates the usual flexible pipe and so shortens the distance and otherwise reduces the area of the passageway from the source of supply to the 55 crucible that an apparatus embodying this feature will operate satisfactorily under con-

ditions that cause prior devices for the same purpose to fail.

Another novel feature consists in an improved organization comprising a movable 60 tank or reservoir and means for guiding it to the flask.

The invention also includes an improved coupling device, and other novel features hereinafter described and claimed and illustrated by the accompanying drawings.

Referring to the drawings,—

Fig. 1 is an elevation of a casting apparatus embodying a preferred form of the invention;

Fig. 2 is a vertical section including a portion of the base, a portion of the fluid-reservoir, the coupling device, and broken lines representing a flask in operative position;

Fig. 3 is a cross-section on line 3—3 of Fig. 2;

Fig. 4 is a perspective view of a preferred type of releasing valve;

Fig. 5 is a horizontal section on line 5—5 of Fig. 1; and

Figs. 6, 7 and 8 are sectional views of flasks of various sizes in which molds have been formed.

The illustrated apparatus comprises a frame having a base 10, a gooseneck 11 and 85 a vertical sleeve or bearing 12 for the fluid-reservoir 13. The latter is cylindric and is adapted to slide up and down in the bearing 12. It is supported by a friction device shown in Fig. 5 and consisting of a leaf spring 14. 90 This spring is a normally flat strip of steel flexed and seated in an internal groove 15 formed in the bearing 12. Its mid-portion bears on the reservoir with sufficient pressure to sustain the latter and all the other 95 elements carried thereby.

The reservoir is provided with a handle 16, a pump 17 and a pressure gage 18. The barrel of the pump is preferably nested in the reservoir for the sake of compactness and extends through the handle 16. The pump plunger projects from the upper end of the barrel and is provided with a handle 19. The discharge end of the pump is in the reservoir and at the lower end of the barrel. By virtue 105 of this construction the reservoir, the pump and the pressure gage form a movable unit.

The base 10, as shown, is formed with three seats 20, 21 and 22 for three sizes of flasks, and with a hole 23 to vent the molds. These 110 seats are formed in stepped relation and are concentric to the reservoir 13. Three flasks,

large, medium and small, are indicated at 24, 25 and 26 in Figs. 6, 7 and 8, respectively, and each is made of metallic tubing. They are also represented by broken lines in Fig. 1 to 5 show how they stand when placed on their respective seats under the reservoir.

The head 30 at the lower end of the cylinder is formed with a nozzle 31 which has telescopic engagement with a coupling member 32. Internal tapering surfaces 33 and 34 are formed in the coupling member to provide seats for external tapering surfaces 35 and 36 at the upper ends of the flasks 25 and 26. To utilize the surface 33 also for the flask 24 the 10 latter is provided with a detachable adapter 37 having an external tapered surface 38 of the same effective proportions as the surface 35. The coupling member 32 and the nozzle 31 are capable of relative axial movement and 15 are slightly loose to enable the coupling member to seat tightly on the flasks. This feature provides for a substantially air-tight joint between the coupling member and any one of the flasks when the reservoir is depressed 20 to operative position. A sleeve 40 of rubber or other soft, elastic and non-porous material is tightly bound to each of the two telescopic elements by metal bands 41 to suspend the coupling member 32, to prevent leakage 25 between the telescopic elements and to permit the aforesaid relative axial movement.

The cylinder head 30 is bored to receive a pressure-sustaining puppet valve which may be of any suitable construction. I prefer a 30 well-known valve designed for pneumatic tires, since it is well suited to the requirements of my invention and may be readily applied. A valve of the type mentioned is indicated at 42 in Fig. 2 and shown separately 35 by Fig. 4. Its body is made of brass or some other soft alloy and is formed with external ribs. By boring the socket for its reception 40 to provide for a tight drive fit the assemblage may be simplified. This valve has a stem 43 which, when pressed in, releases the air or 45 other fluid.

The coupling member 32 carries valve-operating means comprising a screw 44. This screw extends through a larger screw 45, and 50 the latter is screwed into a bushing 46 having ducts 47. The bushing is driven tightly into the bore of the coupling member. After the parts have been assembled the screw 44 is adjusted close to but not to touch the valve- 55 stem 43 except when the compressible sleeve 40 is compressed axially as hereinafter explained. The shank of the screw 45 extends through a hole in a disk 48 of sheet metal which acts as a baffle to spread the released 60 fluid that issues from the ducts 47. The head of the screw clamps the disk against the bushing 46.

For castings of the kind under consideration the matrix or mold 50 is usually formed 65 in an investment 51 of plaster which is suffi-

ciently porous to permit the air to escape from the matrix as the molten metal enters the latter. As shown in Figs. 6, 7 and 8, a crucible 52 is formed in the upper end of the investment, and a small gate or sprue-hole 70 53 forms communication from the crucible to the matrix.

When the matrix is ready to be used to make a casting the user places the necessary metal in the crucible and places the flask on 75 its seat in the base 10. He also operates the pump 17 to charge the reservoir with the desired pressure, say from five to fifteen pounds, according to the area of the matrix. The reservoir now occupies its upper position, as 80 shown by Fig. 1, the coupling member 32 being from one to three inches above the top of the flask.

Now, with one hand grasping the handle 85 16 of the reservoir, the user directs the flame of a blow-torch on the metal in the crucible, and when the metal is fully liquefied he depresses the reservoir with a quick motion and with a follow-through pressure. This carries the coupling member 32 through the 90 flame to the flask, and forms a substantially air-tight joint between the reservoir 13 and the flask. The follow-through pressure exerted on the reservoir compresses the sleeve 40 axially, and the slight downward travel 95 of the reservoir after the flask arrests the coupling member causes the screw 44 to arrest the valve-stem 43 and open the valve. The fluid pressure in the reservoir is thus released almost simultaneously with the coupling of 100 the reservoir and the flask, and furthermore, is released at a point so close to the crucible that no considerable time is lost between the instant of release and the development of working pressure in the crucible.

The released fluid has merely to travel 105 through the short ducts 47 to enter the cavity in which the molten metal is awaiting the working pressure. The inrushing fluid is formed into a conical sheet by the baffle plate 110 48, and instead of blowing the molten metal away from the gate or sprue-hole 53 keeps it centered in the crucible while the pressure rises. As the working pressure develops in 115 the crucible it forces the molten metal into the matrix, the air initially contained in the latter leaking out through the pores of the investment. The entire operation, from the moment the reservoir is depressed, occurs in a fraction of a second but varies according to 120 the area of the matrix.

What I claim is:

1. An apparatus of the character described comprising a flask, a reservoir having a filling means carried thereby for storing fluid under pressure, said flask and said reservoir being relatively movable one toward the other to effect operation and having mated coupling elements adapted to form a fluid-tight connection through which fluid may flow from the 125 130

reservoir into the flask, a pressure-sustaining valve carried by said reservoir and normally preventing the escape of fluid through the coupling element of said reservoir, and means operable by relatively moving the reservoir and the flask toward one another to open said valve.

2. An apparatus of the character described comprising a flask, a reservoir having a filling means carried thereby for storing fluid under pressure, said flask and said reservoir being relatively movable one toward the other to effect operation, said reservoir having a discharge nozzle fixed relatively thereto, a coupling member in telescopic relation to said nozzle and movable lengthwise of its axis, said member and said flask having mated coupling formations adapted to form a fluid-tight connection, a valve carried by said reservoir and normally preventing the escape of fluid through said nozzle, and means operable by relative movement of said coupling member and said reservoir one toward the other to open said valve.

3. An apparatus of the character described comprising a flask, a reservoir having a filling means carried thereby for storing fluid under pressure, said flask and said reservoir being relatively movable one toward and from the other to couple them and having mated coupling elements adapted to form a fluid-tight connection through which fluid may flow from the reservoir into the flask, means to register the flask and the reservoir so that said coupling elements will go into cooperative relation, a pressure-sustaining valve in the discharge end of said reservoir, and means operable by relative movement of said reservoir and flask one toward the other, while said coupling elements are coupled, to open said valve.

4. An apparatus of the character described comprising a movable reservoir for storing fluid under pressure and constructed to carry its full supply of air bodily therewith, said reservoir having a discharge nozzle fixed relatively thereto, a pressure-sustaining valve arranged in said nozzle, a coupling member surrounding and telescopically related to said nozzle to cooperate with a flask, and means operable by relative telescopic movement of said coupling member and said nozzle to open said valve.

5. An apparatus of the character described comprising a movable reservoir having a filling means carried thereby for storing fluid under pressure, means to register a flask relatively to said reservoir, means for guiding said reservoir to and from said flask, a pressure-sustaining valve arranged in said reservoir, and coupling means carried by said reservoir to form a fluid-tight connection with the flask, said coupling means being movable relatively to said reservoir to open said valve in consequence of being arrested by the flask.

6. An apparatus of the character described comprising a movable reservoir for storing fluid under pressure and constructed to carry its full supply of air bodily therewith, said reservoir having a discharge nozzle fixed relatively thereto and a pressure-sustaining valve to control the discharge of fluid therethrough, a coupling member in telescopic relation to said nozzle, resilient means arranged to form a fluid-tight joint between said coupling member and said nozzle and to urge said coupling member toward the outer end of said nozzle, and means carried by said coupling member to open said valve in consequence of relative telescopic movement of said coupling member toward the inner end of said nozzle.

7. An apparatus of the character described comprising a movable reservoir for storing fluid under pressure and constructed to carry its full supply of air bodily therewith, said reservoir having a discharge nozzle and a pressure-sustaining valve to control the discharge of fluid therethrough, a coupling member in telescopic relation to said nozzle, a sleeve of compressible non-porous material forming a pressure-tight joint between said nozzle and said coupling member, and means carried by said coupling member to open said valve in consequence of relatively moving said reservoir and said coupling member to compress said sleeve axially.

8. An apparatus of the character described comprising a reservoir for fluid under pressure, a coupling member carried thereby and having a series of concentric frusto-conical surfaces arranged to make fluid-tight connection with flasks of various diameters, a support having concentric formations to register flasks of various diameters with said coupling member, said reservoir and said support being relatively movable one toward and from the other, guiding means to direct such relative movement, and a pressure-sustaining valve to control the discharge of fluid from said reservoir through said coupling member.

9. An apparatus of the character described comprising a movable unit, means to support and register a flask, relatively thereto, and means to guide said unit toward and from the flask, said movable unit comprising a reservoir having a filling means carried thereby for storing fluid under pressure, a coupling member carried by the reservoir for supplying fluid from the reservoir to the flask, and a pressure-sustaining valve operable by said coupling member to release the fluid from the reservoir so that it may flow through said coupling member to the flask.

10. An apparatus of the character described comprising a movable unit, means to support and register a flask relatively thereto, and means to guide said unit toward and from the flask, said movable unit comprising a reservoir for storing fluid initially under pressure,

a pump for charging the reservoir with fluid, a coupling member carried by the reservoir for supplying fluid from the reservoir to the flask, and a pressure-sustaining valve operable by said coupling member to release the fluid from the reservoir so that it may flow through said coupling member to the flask.

11. An apparatus of the character described comprising a movable unit, means to support and register a flask relatively thereto, and means to guide said unit toward and from the flask, said movable unit comprising a reservoir for storing fluid initially under pressure, a pump nested in said reservoir to charge the reservoir with fluid, said pump having an operating handle outside the reservoir, a coupling member carried by the reservoir for supplying fluid from the reservoir to the flask, and a pressure-sustaining valve operable by said coupling member to release the fluid from the reservoir so that it may flow through said coupling member to the flask.

12. An apparatus of the character described comprising a vertically movable unit, means to guide said unit, means to register a flask relatively to said unit, and friction means to support said unit so that it may be depressed

manually to engage the flask, said unit comprising a reservoir having a filling means carried thereby for storing fluid under pressure, coupling means carried thereby to supply fluid from the reservoir to the flask, and a pressure-sustaining valve operable by said coupling means to release the fluid from the reservoir so that it may flow through said coupling means to the flask.

13. An apparatus of the character described comprising a flask, a movable reservoir for storing fluid under pressure and constructed to carry its full supply of air bodily therewith, coupling means attached to said reservoir to supply fluid to said flask, said coupling means and said flask having cooperative portions to form a fluid-tight connection, a valve to control the release of fluid from the reservoir to said flask, and a baffle member arranged in and secured to said coupling means to deflect the inrushing fluid from the center toward the perimeter of the flask.

In testimony whereof I have affixed my signature this 31st day of July, 1926.
